GIBBONS G. HICKMAN, OF COATESVILLE, PENNSYLVANIA, ASSIGNOR TO
HIMSELF AND GEORGE WINDLE, OF SAME PLACE.

Letters Patent No. 73,893, dated January 28, 1868.

IMPROVED SHUTTER-FASTENING.

The Schedule referred to in these Letters Patent and making part of the same.

TO ALL WHOM IT MAY CONCERN:

Be it known that I, GIBBONS G. HICKMAN, of Coatesville, in the county of Chester, and State of Pennsylvania, have invented a new and useful Improvement in Shutter-Fastenings; and I do hereby declare the following to be a full, clear, and exact description of the same, reference being had to the accompanying drawing, which is made a part of this specification.

The subject of this invention is a shutter-fastening, by means of which the shutters can be secured in their closed position, or held in any desired bowed or partially-opened position. It consists in the employment of an elastic perforated metallic strap, in connection with a hitching-pin and button, the flexibility of the metallic strap adapting it to connect the shutters in any bowed position in which it may be desired to retain them, or to secure them in their closed position, as hereinafter explained.

The drawing is a perspective view, the spectator beholding the bowed shutters and the fastening from the interior of the room.

A A represent a pair of window-shutters, and B B' two metallic plates secured thereto, for the purpose of affording a means for attaching the fastening-device. This fastening consists of an elastic metallic strap, C, attached to the plate B' by a pivot, b, a round, square, or other suitably-formed stud or pin, D, projecting rigidly from the plate B, and a button or latch, E, whose shank is pivoted to the plate B. F F' are rings, attached respectively to the head of the pivot b, and to the button E. These rings enable the operator to turn the strap C and button E to the desired position, and at the same time to push the shutters open or pull them to. The strap C is provided with a series of apertures or perforations, e, any one of which may be made to engage over the stud D, such engagements being maintained by turning down the button E, so as to prevent the inward movement of the strap C. The flexibility of the strap C adapts it to bend, so as to make any of its holes e engage with the stud D, and thus fasten the shutters when entirely closed, or retain them in any desired bowed position. The stud D should project beyond the strap C, sufficiently to form a stop to arrest the button E, when closed upon the strap.

Having thus described my invention, what I claim herein as new, and desire to secure by Letters Patent, is—

1. The elastic strap or connection, C, substantially as and for the purpose explained.
2. The combination of the elastic strap C, stud D, and button or latch E, arranged and operating substantially as described.
3. In combination with the subject of the preceding clause, I claim the rings F F', applied in the manner and for the purpose set forth.

To the above specification of my new and useful improvement in shutter-fastenings, I have signed my hand, this 28th day of June, A. D. 1867.

G. G. HICKMAN.
